(57) **CLAIM**

We claim the ornamental design for a barbecue grill, as shown and described.

DESCRIPTION

FIG. 1 an isometric view taken from the front upper right, showing my new design for a first embodiment of a barbecue grill.

FIG. 2 is a front elevational view thereof.

FIG. 3 is a top plan view thereof.

FIG. 4 is a right side elevational view thereof.

FIG. 5 is a left side elevational view thereof.

FIG. 6 is a bottom view thereof.

FIG. 7 is a rear elevational view thereof.

FIG. 8 an isometric view taken from the front upper right, showing my new design for a second embodiment of the barbecue grill.

FIG. 9 is a front elevational view thereof.

FIG. 10 is a top plan view thereof.

FIG. 11 is a right side elevational view thereof.

FIG. 12 is a left side elevational view thereof.

FIG. 13 is a bottom view thereof; and,

FIG. 14 is a rear elevational view thereof.
